ROLLER SUPPORTING BRACKET

Walter J. Stuber, Philadelphia, Pa., assignor to
Carey-McFall Co., Philadelphia, Pa., a corpora-
tion of Pennsylvania

Application October 3, 1932. Serial No. 636,073

18 Claims. (Cl. 156—24)

This invention relates in general to brackets employed in supporting spring-loaded rollers, such, for example, as those used in connection with window shades, etc., and more particularly 5 to the type utilized to hang the curtains of automobiles and other vehicles of the closed types.

The principal object of the present invention is to provide brackets which will firmly hold the roller pivots or trunnions, and particularly the 10 pivot to which one end of the operating spring of the roller is anchored, for the purpose of preventing wobbly action of the roller and to prevent rattling or other undesirable noises ordinarily produced by relative movement between the 15 trunnions and their supporting brackets as a result of vibrations occurring in the bodies of the vehicles.

The present invention is particularly adaptable for use with rollers having trunnions of the 20 type shown and described in the applicant's co-pending applications, Serial No. 636,071, and Serial No. 636,072, filed respectively on October 3, 1932, each of which, and the present application, 25 are continuations in part of the applicant's prior application, Serial No. 580,706, filed December 11, 1931.

In the accompanying drawing:

Fig. 1 is a perspective view of a bracket made 30 in accordance with the principles of the present invention;

Fig. 2 is a sectional elevation taken on the line 2—2, Fig. 1;

Fig. 3 is a view similar to Fig. 2, but showing 35 a roller trunnion in position in the bracket; and

Fig. 4 is a sectional plan view taken on the line 4—4, Fig. 3.

The bracket forming the subject of the present application is composed of two sheet metal stampings, 1 and 2 respectively, which are rigidly secured together in a manner to prevent relative movement therebetween.

The stamping 1 comprises a substantially flat base or foot 10 having a substantially right angle flange 11 extending around the greater portion 45 thereof. The base 10 is provided with a pair of relatively spaced centrally apertured concavities 12, 12 affording countersunk openings 13, 13 for the reception of screws or other fastening means whereby the bracket may be secured in a roller-supporting position.

Formed integral with and extending substantially at right angles to the base 10 is a substantially flat neck 14 which terminates, in the present instance, in a hollow dish-like head or shield 55 15 that is provided with an outwardly projecting

flange 16 disposed in substantially the same plane as the flat neck portion 14 of the bracket.

The outer edge 17 of the flange 16 is bent inwardly to a plane substantially paralleling that of the said flange, thereby providing a groove 60 18 that is adapted to receive a substantially flat head plate 20 which forms the major portion of the stamping 2. The outer edge of the head plate 20 is seated in the groove 18 and is rigidly secured therein by the inturned edge 17 of the 65 flange 16 when the said edge 17 is bent around the said outer edge of the plate 20 and pressed inwardly over the plate toward the base of the flange.

Extending from one side and in the plane of 70 the head plate 20, along and adjacent the neck 14 and conforming to the general shape thereof, is an ear 21. The opposite edges of the ear 21 are seated in grooves 18a, 18a respectively which are formed along the opposite sides of the neck 14 75 by turning the outer edges 17a, 17a on said neck over the corresponding edges of the ear 21, the grooves 18a, 18a of the neck 14 forming continuations of the groove 18 that extends around the hollow head 15, the inturned edges 17a, 17a 80 of the neck 14 constituting continuations of the inturned edge 17 of the flange 16 of the said head.

The stamping 2, particularly, is composed of 85 relatively stiff sheet metal, such as iron, steel, brass, etc. having a substantial degree of inherent resiliency, or capable of being tempered or otherwise hardened to provide such resiliency as may be required for purposes hereinafter set forth.

The head plate 20 is provided with an opening 90 25 which is adapted to receive one of the trunnions x of a spring-loaded roller X, as illustrated in Figs. 3 and 4.

In the present instance, the trunnion x is rotatably mounted in one end of the roller X and is provided with a projecting end that is of rectangular cross section. The particular trunnion illustrated in the present case is the one to which one end of the operating spring of the roller is 95 anchored, the opposite end of the spring being anchored to the barrel of the roller, the trunnion, therefore, is arranged to be nonrotatably supported by the bracket to provide for rotation of the roller in one direction by the spring confined within the roller, the roller revolving on and about the fixed trunnion.

In order to accommodate the rectangular cross section of the trunnion x and to prevent rotation of the trunnion relative to the bracket, the 110 100 105 110

- opening 25 in the head plate 20 is correspondingly of rectangular form, the length and the width of the said opening 25 being such as to snugly fit the rectangular end of the trunnion x.
5. In order to prevent relative lateral movement between the trunnion x and the bracket and to provide a firm bearing for and longitudinally of the trunnion one or more of the sides of the opening 25 is provided with a spring tongue 26.
10. In the present instance a pair of such tongues are respectively disposed at opposite ends of the opening 25, in opposed relation to each other, and extend substantially at right angles to and from the plane of the head plate 20, said tongues projecting into the dish-like head 15 of the bracket and firmly clamping the trunnions therebetween. The tongues 26, 26 afford such sturdy support for the trunnion that the trunnion is held rigidly in a position perpendicular to the head plate, permitting free rotation of the roller without permitting any wobbly action thereof.
- For the purpose of the present invention the planes of the tongues 26, 26 are slightly convergent, in order that the said tongues will press firmly against opposite sides of the trunnion x when the said trunnion is inserted within the opening 25 of the bracket, as illustrated in Fig. 3, whereby the tongues 26, 26 are spread from their convergent relation shown in Fig. 2 to the substantially parallel relation shown in Fig. 3. Such construction and cooperation of parts eliminates any play or relative movement between the trunnion and the bracket, such as may result from slight variations between the cross sectional dimensions of the trunnion and the opening within the limits prescribed by the manufacturers' tolerances, thus any rattling or other undesirable noises resulting therefrom will be eliminated.
40. In the present instance, the spring tongues 26, 26 are formed as integral parts of the head plate 20 and the resiliency of the sheet metal of which the stamping 2 is formed provides the necessary resiliency in the tongues 26, 26 to permit the said tongues to yield as the trunnion is inserted therebetween and at the same time cause the tongues to grip the trunnion firmly at oppositely disposed points, to prevent relative movement between the trunnion and the bracket and to support the trunnion in rigid perpendicular relation to the head plate of the bracket to avoid any wobbling or looseness as the roller is rotated about the pivot or trunnion.
- The tongues 26, 26 and the opening 25 may be readily produced by forming an H shaped slit in the head plate and bending the two portions lying between the side slits at opposite sides of the cross slit outwardly in opposite directions along lines parallel to the cross slit and connecting the opposite ends of the parallel side slits.
45. As shown in Figs. 3 and 4, the hollow dish-like head 15 serves as a means for completely hiding the end of the trunnion and the spring tongues from view.
50. I claim:
1. A roller-supporting bracket having an opening to receive a pivot of said roller and resilient means adjacent the opening to bear against the pivot and prevent lateral movement thereof in said opening.
  2. A roller-supporting bracket having an opening to receive a pivot of said roller and resilient means at predetermined points around said opening to bear against the pivot and prevent lateral movement thereof in said opening.
  3. A roller-supporting bracket having an opening to receive a pivot of said roller and resilient means at diametrically opposed points around said opening to bear against the pivot and prevent lateral movement thereof in said opening. 80
  4. A roller-supporting bracket having an opening to receive a pivot of said roller and a spring tongue adjacent the opening to bear against the pivot and prevent lateral movement thereof in said opening. 85
  5. A roller-supporting bracket having an opening to receive a pivot of said roller and a spring tongue adjacent and extending substantially parallel to the axis of the opening, the tongue to bear against the pivot and prevent lateral movement thereof in said opening. 90
  6. A roller-supporting bracket having an opening to receive a pivot of said roller and a spring tongue adjacent and extending substantially parallel to the axis of the opening and inclined toward said axis, the tongue to bear against the pivot and prevent lateral movement thereof in said opening. 95
  7. A roller-supporting bracket comprising a plate having an opening to receive a pivot of said roller and a spring tongue projecting outwardly from said plate to bear against the pivot and prevent lateral movement thereof in the opening. 100
  8. A roller-supporting bracket comprising a plate having an opening to receive a pivot of said roller, and a plurality of spring tongues relatively spaced about the opening and extending outwardly from one side of the plate to bear against the pivot and prevent lateral movement thereof, in said opening. 105
  9. A roller-supporting bracket comprising a plate having an opening to receive a pivot of said roller, and a plurality of spring tongues relatively spaced about the opening and extending outwardly and convergently from one side of the plate to bear against the pivot and prevent lateral movement thereof in said opening. 115
  10. A roller-supporting bracket comprising a plate having an opening to receive a pivot of said roller, and a pair of spring tongues in diametrically opposed relation about the opening and projecting outwardly from one side of the plate to bear against opposite sides of the pivot and prevent lateral movement thereof in the opening. 120
  11. A roller-supporting bracket comprising a plate having an opening to receive a pivot of said roller, and a pair of spring tongues in diametrically opposed relation about the opening and projecting outwardly and convergently from one side of the plate to bear against opposite sides of the pivot and prevent lateral movement thereof in the opening. 125
  12. A roller-supporting bracket comprising a plate and a tongue forming part of the plate and bent at an angle to the plane of the plate providing an opening in the plate for reception of a pivot of the roller, said tongue to bear against the pivot to prevent lateral movement of the pivot in the opening. 130
  13. A roller-supporting bracket comprising a plate and a pair of tongues forming part of the plate and bent outwardly from and at angles to the plane of the plate providing an opening in the plate for the reception of a pivot of the roller and arranged to bear against opposite sides of the pivot to prevent lateral movement of the pivot in the opening. 145
  14. A roller-supporting bracket comprising a 150

- plate and a pair of tongues forming part of the plate and bent outwardly from and at converging angles to the plane of the plate providing an opening in the plate for the reception of a pivot 5 of the roller and arranged to bear against opposite sides of the pivot to prevent lateral movement of the pivot in the opening. 15. A roller-supporting bracket comprising a plate and a pair of tongues forming part of the plate and bent outwardly from and at angles to the plane of the plate providing an opening in the plate for the reception of a pivot of the roller and arranged to bear against opposite sides of the pivot to prevent lateral movement of the pivot 10 in the opening, a dish-like shield covering one side of the plate and the tongues projecting therefrom and provided with a groove receiving the outer edge of the plate, and means for securing the bracket in roller-supporting position. 15. A roller-supporting bracket comprising a plate element having a pair of tongues formed therein and bent outwardly therefrom to produce an opening in the plate for receiving a pivot of the roller and to bear against the pivot to prevent lateral movement thereof in said opening, a dish-like shield element at one side of the plate and covering the tongues extending therefrom, and a foot formed on one of said elements for securing the bracket in roller-supporting position. 20 16. A roller-supporting bracket comprising a plate element having a pair of tongues formed therein and bent outwardly therefrom to produce an opening in the plate for receiving a pivot of the roller and to bear against the pivot to prevent lateral movement thereof in said opening, a dish-like shield element at one side of the plate and covering the tongues extending therefrom, and a foot formed on one of said elements for securing the bracket in roller-supporting position. 25 17. A roller-supporting bracket comprising a plate element having a pair of tongues formed 30
- therein and bent outwardly therefrom to produce an opening in the plate for receiving a pivot of the roller and to bear against the pivot to prevent lateral movement thereof in said opening, a dish-like shield element at one side of the plate and covering the tongues extending therefrom and provided with a groove in which the outer edge of the plate is secured, a neck on each of said elements with one of said necks provided with grooves along its opposite edges to receive the edges of the other of said necks, and a foot on one of said necks for securing the bracket in roller-supporting position. 80 18. A roller-supporting bracket comprising a plate element having a pair of tongues formed therein and bent outwardly therefrom to produce an opening in the plate for receiving a pivot of the roller and to bear against the pivot to prevent lateral movement thereof in said opening, a dish-like shield element at one side of the plate and covering the tongues extending therefrom and provided with a groove in which the outer edge of the plate is secured, an ear on and projecting from the plate in the plane thereof, a neck on the dish-like element having grooves along its opposite edges in line with the groove of the dish-like element and receiving the edges of the ear of the plate element, and a foot on said neck for securing the bracket in roller-supporting position. 85 90 95 100 105
